AMUSEMENT APPARATUS

Walter A. Tratsch, Chicago, Ill., assignor to Clarence E. Threedy, Chicago, Ill., as trustee

Application May 17, 1945, Serial No. 594,298

5 Claims. (Cl. 46—122)

This invention relates to amusement apparatuses. More specifically the invention relates to a mechanism for providing a staggered and intermittent movement of a plurality of objects each simulating a race horse or a greyhound or other animal or character, over an unobstructed track, and to this end it is sought by this invention to accomplish the foregoing by a structure which is simple and economical in manufacture, requiring the minimum number of parts for effective operation.

Other objects will appear hereinafter.

The invention consists in the novel combination and arrangement of parts to be hereinafter described and claimed.

The invention will be best understood by reference to the accompanying drawings showing the preferred form of construction and in which:

Fig. 1 is a plan view of the amusement apparatus embodying the invention;

Fig. 2 is a longitudinal vertical sectional detail view taken substantially on line 2—2 of Fig. 1;

Fig. 3 is a sectional detail view taken substantially on line 3—3 of Fig. 1;

Fig. 4 is a sectional detail view of the same taken substantially on line 4—4 of Fig. 3;

Fig. 5 is a sectional detail view of the same taken substantially on line 5—5 of Fig. 2;

Fig. 6 is a diagrammatical plan view of a suggested circuit arrangement embodied in the invention.

The drawings illustrate the preferred form of construction by which the several objects of this invention are accomplished. In this connection a suitable mounting plate is indicated at 10. Positioned at one end of this mounting plate is a U-shaped bracket 11, the end portions 12 of which are arranged in parallel relation with respect to each other to provide spaced bearings for a driven shaft 13 extending through the mounting plate 10 and extending vertically thereabove. The lower end portion of this shaft 13 is slotted as at 15 for the reception of a key 16 carried by the driving shaft 17, which driving shaft 17 is rotated by a suitable driving power, such for example, an electric or spring motor (not shown). The major length of this shaft 13 is provided with a longitudinal slot 18 for reasons hereinafter set forth. Positioned upon the shaft 13 and fixed thereto by means of a suitable set screw 19 and located adjacent the lower end portions 12 of the bracket 11 is a collar 20.

Upon this shaft 13 in spaced relation with respect to each other are arranged a plurality of

driving discs 21. Each disc 21 supports a pulley 22. Each disc 21 provides a central hub 23 projected through an opening 24 formed in the pulley 22 supported by the disc. Each hub 23 extends slightly above the top surface 25 of the adjacent pulley 22 so that the hubs are in effect resting one upon the other and support the discs 21 in spaced relation from the pulleys 22, as best shown in Fig. 3. Each hub 23 is provided with a transverse web 26 which fits into the longitudinal slot 18 formed in the shaft 13 whereby to provide driving connection between the discs 21 and the shaft 13. Each pulley comprises a groove 27 and a ratchet gear 28. In the grooves 27 of the pulleys work continuous ribbon-like belts 29.

At the opposite end of the mounting plate 10 there is secured a substantially U-shaped bracket 30, the end portions 31 of which provide suitable bearings for the ends 32 of a shaft 33 disposed between the end portions 31. On this shaft 33 there is arranged a plurality of pulleys 34 spaced from each other by suitable collars 35 disposed between the pulleys as shown. The top and bottom pulley of the pulleys 34 are spaced from the end portions 31 of the bracket 30 by suitable bushings 36. These pulleys 34 each comprise grooves 37 in which work the continuous ribbon-like belts 29.

The lowermost of the discs 21 (as shown in Fig. 3) rests upon the collar 20 fixed to the shaft 13 by the set screw 19.

The arrangement is such that when the shaft 13 is rotated by the shaft 17, the pulleys 22, resting upon the driving discs 21, will rotate with the discs 21 except when prevented from doing so in a manner now to be described.

Fixed to the mounting plate 10 is a supporting bracket 38. Carried by this bracket 38 are a plurality of independently operated solenoids 39 each comprising a solenoid shaft 40 adapted to successively engage the ratchet gears 28 of the pulleys 22 to momentarily hold one of the pulleys against rotation with its respective driving or supporting disc 21.

This successive engagement between the solenoid shafts 40 and the ratchet gears 28 may be accomplished in any suitable manner, but for the purpose of illustration I have shown in Fig. 6 a circuit diagram capable of this accomplishment. In this connection, 41 indicates a motor-driven switch arm, the motor being indicated at 42 and arranged in an electric circuit 43, in which circuit there is a master switch 44 to control operation of the motor 42. This switch arm 41 is

adapted, in the present instance, to engage contact buttons 45 having connection with the solenoids. The opposite side of these solenoids is connected by the circuit conductors 47 to the source of electric energy 48.

The arrangement is such that upon engagement between the switch arm 41 and one of the contact buttons 45, the solenoid coil connected to such button will be energized and the solenoid shaft 40 projected into engagement with the gear 28 to momentarily hold the pulley with which that gear is associated, against rotation with its driving or supporting disc. This will permit the remaining belts 29 to rotate while the belt of the pulley thus restrained from rotation will momentarily remain stationary. While I have illustrated in Fig. 6 that the buttons 45 are successively engaged, it is obvious that an arrangement may be adopted for alternately engaging such buttons.

Secured to each of the belts 29 is a spring-like supporting wire 49 which supports a suitable object 51, which object may simulate a race horse, greyhound or other racing animal. This racing object may be supported from its respective wire support 49 in a manner substantially similar to that disclosed in application, Serial No. 574,486, filed January 25, 1945.

To complete the invention, a suitable structure is provided to simulate a race track R. In this connection it is one of the objects of this invention to support this race track in a manner such as would not interfere with the movement of the wires 49 by the belts 29. To accomplish this object, there is provided a plurality of rod-like elements 52 equally spaced from each other as best shown in Figs. 1, 2 and 5, to provide guideways 52', which in the present instance are substantially oval-shaped in plan view and between which the wires 49 project and move.

These rod-like members 52 are arranged concentrically with respect to each other to simulate a race track. These rod-like members 52 are supported by bars 53 arranged in spaced parallel relation with respect to each other and bent to provide vertical end portions 54 secured to the rod-like members 52 are connected by soldering or the like. These bars 53 are further bent to provide horizontal end portions 55 secured to plates 56 carried by the brackets 11. As the bars 53 are concentric with respect to each other and support the track rods 52 in concentric relation with respect to each other, it is manifest that the guideways 52' between each of the track rods 52 and bars 53 are unobstructed, thus permitting the wires 49 to move through the passages 57 free from any interference.

The operation of the amusement apparatus is as follows:

Upon rotation of the shaft 13 the pulleys 22, by reason of their frictional engagement with the discs 21, will be caused to rotate and in turn the belts 29 will travel around these pulleys and the pulleys 34. As the belts 29 travel around the pulleys 22 and 34, the supporting wires 49 will move along the track provided by the track rods 52 and carry the racing object 51 therewith. Upon operation of the motor 42, the switch arm 41 will be successively brought into contact with the conductor buttons 45 and successively effect energization of the solenoid coils 46, thus successively projecting the solenoid shafts 40 into engagement with the ratchet gears 28, momentarily restraining rotation of one of the pulleys 22.

While restrained, the belt of that pulley, 29, will momentarily stop traveling and consequently the racing object carried thereby will likewise momentarily stop moving, thus permitting the other racing objects to advance forward of the racing object momentarily stopped. By this arrangement, the racing objects may advance ahead of one another, thus simulating a fast-moving object and one which has been slowed up or momentarily stopped. As before stated, while I have not indicated the mechanism for alternately engaging the conductor buttons 45, such mechanism may be provided without departing from the spirit of this invention.

From the foregoing description, it is apparent that there is provided an amusement apparatus in which the racing objects may gain or lose according to the degree of rotation of the pulleys 22 controlling their movement over a track simulated by the track rods 52.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A structure simulating a race track comprising a plurality of horizontally disposed members having portions arranged concentrically and in spaced relation with respect to each other, a pair of supporting brackets spaced from each other, and members extending from said brackets in spaced parallel relation with respect to each other and having end portions connected to such first named members and providing therebetween unobstructed passages.

2. A structure simulating a race track comprising a mounting plate, spaced bracket members at opposite end portions of the mounting plate, rod members arranged in concentric vertical relation with respect to each other and having horizontal parallel portions connected to said bracket members and opposite end portions extending in parallel spaced relation with respect to each other, and rod members arranged in horizontal concentric spaced relation with respect to each other and having connection with the vertical end portions of said first-named rod members.

3. A structure simulating a race track comprising a plurality of oval-shaped rod members arranged in horizontal spaced relation with respect to each other, a pair of spaced bracket members located centrally with respect to said rod members, spaced rod members extending from said brackets in concentric spaced relation with respect to each other and having end portions secured to said first-named rod members for supporting said first-named rod members with respect to each other to simulate a race track.

4. A structure simulating a race track comprising a mounting place bracket element on said plate, supporting means carried by and extending laterally and upwardly from opposite sides of said bracket element and having spaced concentrically arranged passages, and a track structure carried by said supporting means and having a plurality of horizontally arranged guideways communicating with the passages, in combination with a

plurality of traveling belts arranged beneath said track structure and having object-supporting means extending laterally therefrom and disposed in said guideways, for movement therealong and adapted to pass through said passages.

5. A structure simulating a race track comprising a mounting plate, bracket elements at opposite ends of said mounting plate and located on a centrally located longitudinal line of said mounting plate, supporting means carried by each of said brackets and extending laterally and upwardly from opposite vertical edges thereof

and providing a plurality of concentrically arranged passages, and a track structure carried by said supporting means and having a plurality of horizontally disposed concentrically arranged guideways communicating with the passages, in combination with a plurality of traveling belts arranged beneath said track structure, and object-supporting members on said belts and adapted to move through said guideways and to pass through said passages.

WALTER A. TRATSCH.
